UNITED STATES PATENT OFFICE.

JOHN MAXWELL, OF ONEIDA, NEW YORK.

DESIGN FOR A COFFIN-PEDESTAL.

SPECIFICATION forming part of Design No. 13,293, dated September 12, 1882.

Application filed August 2, 1882. Term of patent 7 years.

To all whom it may concern:

Be it known that I, JOHN MAXWELL, of Oneida, in the county of Madison, in the State of New York, have invented and produced a new and original Design for a Coffin-Pedestal, of which the following, taken in connection with the accompanying drawings, is a full, clear, and exact description.

This design pertains to a pedestal for supporting burial caskets and coffins; and it consists essentially of a column having an octagon body or shaft trimmed on its respective sides with a spiral semi-columnar molding, which is extended the height thereof and parallel with the axis of the column, and which is to be covered or faced with any suitable textile fabric, and to have a continuous cord wound around the molding over the cloth facing thereof and drawn into the indentations of the molding.

In the annexed drawings, Figure 1 is an elevation of my design, and Fig. 2 is a horizontal transverse section of the same on line x x.

A represents the body or shaft of the column, formed octagon shape in cross-section, as shown in Fig. 2 of the drawings. B is the spiral semi-columnar molding, and C and D are respectively the base and capital of the column.

The octagon shaft of the column, trimmed with the spiral semi-columnar molding, as above described, produces a highly ornamental and pleasing effect.

The base and capital of the column may be embellished correspondingly by placing upon the top of the plinth and around the abacus a semi spiral columnar molding similar to that above described; but it is not an essential part of the design.

What I claim as new is—

The design for a coffin-pedestal, consisting of a column having an octagon shaft trimmed on its several faces with spiral semi-columnar moldings, as shown and described.

In testimony whereof I have hereunto signed my name and affixed my seal, in the presence of two attesting witnesses, at Syracuse, in the county of Onondaga, in the State of New York, this 26th day of July, 1882.
